UNITED STATES PATENT OFFICE.

GLENN A. MORRELL, OF SEATTLE, WASHINGTON, ASSIGNOR OF ONE-HALF TO CHARLES W. RODGERS, OF SEATTLE, WASHINGTON.

FIREPLACE DAMPER.

1,422,465.

Specification of Letters Patent. Patented July 11, 1922.

Application filed January 18, 1922. Serial No. 530,034.

To all whom it may concern:

Be it known that I, GLENN A. MORRELL, a citizen of the United States of America, and resident of the city of Seattle, in the county 5 of King and State of Washington, have invented certain new and useful Improvements in Fireplace Dampers, of which the following is a specification.

My invention relates to fireplace dampers. 10 It comprises certain novel features of construction and combinations of parts which will be hereinafter described and then particularly pointed out in the claims.

The object of my invention has been to 15 produce a damper of simple design which may be cheaply constructed, which will be durable in use and simple and easy to operate.

In the accompanying drawings I have 20 shown my invention in its preferred form of construction.

Figure 1 shows the damper in sectional elevation.

Figure 2 is a top plan view of the damper 25 showing the damper plate raised.

Figure 3 shows in perspective a half length of the damper, the damper plate and its supporting bar being in section.

In the drawings 1 represents the chimney 30 flue. The damper plate 2 is pivoted at one side of the throat of the chimney so as to swing upwardly. As a practical method of installing the damper, it may be pivoted to a bar 3 which is preferably of an L-shape 35 in cross section and serves as an angle bar or support for the masonry at the top of the fireplace opening. This should be of such length that its ends have ample support upon the masonry at opposite ends of the fireplace opening.

Projecting rearwardly from the masonry, just above the fireplace opening and preferably at about the center of the length of said opening is a ratchet bar 4. This has 45 ratchet teeth 40 on its upper edge and also preferably a return bend or hook 41 at its rearward end.

Pivottally secured to the lower side of the damper plate 2 is an arm 5. This arm has 50 a bolt 49 which is adapted to engage with the notches 40 of the ratchet bar 4 so as to support the damper plate in adjusted positions. In the position shown in Figures 1 and 3 the damper is entirely closed. In 55 such position the part 50 of the lever 5

which engages with the ratchet bar 4, and which is shown as a roller journaled on a bolt 49, engages with the outermost of said notches 40. It also, in this position, extends under the return hook 41 and prevents the possibility of swinging the arm 5 outwardly so as to disengage it from the ratchet bar.

The arm 5 extends downwardly to such a point that it may be seen and manipulated 65 through the fireplace opening. It is also preferably provided with a loop as 51 so that it may be conveniently engaged by a hook formed on the end of a poker or other bar. To prevent displacement of the arm 5 70 from the ratchet bar 4 it may be provided with a slot 52 of such size as to accommodate the ratchet bar. This slot is passed over the ratchet bar and the arm 5 is thus held in position.

The closed position of the damper plate is shown in Figures 1 and 3. To raise the damper the arm 5 is engaged and pulled forwardly. This causes the part 50 which engages with the upper edge of the ratchet bar 80 to slide up the toothed upper surface of the bar 4. The bar 5 may be stopped in engagement with any one of the notches 40. As the arm 5 proceeds forwardly relative to the bar 4, the damper is held in the successively higher positions by the engagement of the part 50 with successive notches 85 40. In its uppermost position the damper plate is held substantially in vertical position. To lower the damper it is only necessary to push the arm 51 towards the rear. The bar will slide down the upper surface 90 of the ratchet bar 4. The notches 40 are purposely made such that the application of a little force rearwardly to the bar 5 will 95 cause it to slide out of the notches and downward.

What I claim as my invention is:

1. A fireplace damper comprising a hinged damper plate, a fixed ratchet bar 100 and an arm hinged to the damper plate outwardly from its pivot and adapted to engage the ratchet bar to hold the damper in raised positions.

2. A fireplace damper as in claim 1 in 105 which the ratchet bar has a terminal hook adapted to prevent displacement of the hinged arm.

3. A fireplace damper comprising an angle section beam extending along the lintel 110

of the fireplace opening, a damper plate hinged at the upper edge of the inner vertical web of said beam, a ratchet bar extending rearwardly from said inner vertical web and an adjusting bar hinged to the damper plate outwardly from its pivot and adapted to engage the ratchet bar to hold the damper plate in adjusted positions.

4. A fireplace damper comprising a damper plate hinged at one side of the fireplace throat, a ratchet arm toothed upon its upper edge extending crosswise of the throat and an adjusting arm pivoted to the damper plate outwardly from its pivot and

adapted to engage the ratchet arm to hold the damper in adjusted position.

5. A fireplace damper as in claim 4 in which the adjusting arm has a slot for the reception of the ratchet arm.

6. A fireplace damper as in claim 4 in which the adjusting arm is slotted to receive the ratchet arm and is provided at its outer end with means for preventing removal of the adjusting arm therefrom.

Signed at Seattle, King County, Washington, this 7th day of January, 1922.

GLENN A. MORRELL.
